UNITED STATES PATENT OFFICE.

MARIE P. HENDERSON, OF NEW YORK, N. Y.

BED.

SPECIFICATION forming part of Letters Patent No. 639,234, dated December 19, 1899.

Application filed May 11, 1899. Serial No. 716,335. (No model.)

To all whom it may concern:

Be it known that I, MARIE POWER HENDERSON, a citizen of the United States, residing at New York, (Brooklyn,) in the county 5 of Kings and State of New York, have invented certain new and useful Improvements in Beds, of which the following is a full and complete specification, such as will enable those skilled in the art to which it appertains 10 to make and use the same.

This invention relates to beds, and has more particular reference to a bed of adjustable length.

The object of my invention is to provide a 15 bed which may normally be of contracted or short length, but capable of longitudinal extension. As ordinarily constructed beds are necessarily made of a length required by the height of the average or above the average occupant, and hence occupy unnecessary space 20 in hotel, dwelling, and other rooms. By my invention a bed may be constructed to normally fit in length the height of persons of short stature or even of a more diminished 25 length and may be readily longitudinally extended when desired.

My invention is fully disclosed in the following specification, of which the accompanying drawings form a part, in which like reference characters denote like parts in the several views, and in which—

Figure 1 is a side elevation of a bed constructed according to my invention; Fig. 2, a plan view thereof; and Fig. 3, an end view 35 thereof, looking in the direction of the arrow, Fig. 1, the upper part of the end supports being cut away.

Referring more particularly to the drawings, I provide end supports which are constructed as follows and provided with uprights *a*, each pair of which is provided with a cross-rod *b*. Connected at each side to one of the uprights *a* is a rigid angular frame, comprising diagonally-inclined sides *c* and 45 end *d* and preferably composed of a single bent bar or tube.

Centrally of the end *d* a leg *e* projects downwardly therefrom, and connected with each of the legs *e* is a length of chain *f*, each of 50 which is provided with a hook *g*, adapted to engage one of the links of the other length of chain.

A mattress-frame having sides *h* and ends *j* rests upon the ends *d* of the frame *c d* between the inclined sides *c*, which prevent 55 lateral movement thereof, and the mattress-frame *h j* is provided with a hinged end portion *k l*, hinged thereto, as at *m*, and adapted, with the bed in contracted position, as in the drawings, to rest upon the frame *h j*. When 60 it is desired to expand the bed longitudinally, one of the supports *a b c* is moved away from the corresponding end of the mattress-frame *h j*, and the hinged end portion *k l* is straightened out to project in the same plane as the 65 frame *h j* and rest rearwardly of the corresponding support-frame end *d*, as shown in dotted lines in Fig. 2.

When the bed is in contracted position, the hook *g* of one of the chains *f* may engage the 70 other chain *f* and prevent longitudinal extension thereof.

It is evident that many changes may be made in the construction and operation of my invention and I claim all such as are 75 within the scope thereof.

Having fully described my invention, I claim as new and desire to secure by Letters Patent—

1. An improved adjustable bed, comprising 80 end supports embodying an inwardly-projecting supplementary frame having sides, a cross-bar connecting said sides and provided with a supporting leg or standard, a mattress-frame having an extensible hinged end portion and 85 adapted to be received within the supplementary portions of said end supports, and chains or flexible connecting means extending longitudinally beneath said mattress-frame and connected to the end supports and adjustable 90 to govern the position of the latter, substantially as and for the purpose set forth.

2. An improved adjustable bed, comprising 95 the end supports embodying the end uprights connected by a cross-bar and having the supplemental inwardly-projecting frame consisting of the side pieces, the cross-bar connecting said side pieces and carrying the leg or standard, the mattress-frame provided with an extensible hinged end portion and adapted to 100 be received within the supplementary portion of the end supports, and the adjusting-chains respectively connected to said leg or standard of the supplementary frame of the end sup-

ports and extending longitudinally beneath the mattress-frame and provided with end hooks, substantially as and for the purpose set forth.

- 5 3. An improved adjustable bed, comprising the end supports embodying the main uprights connected by a cross-bar and provided with the inwardly-projecting supplementary frame consisting of the inclined sides, the cross-bar connecting said sides and carrying the central leg or standard, and the adjusting-chains respectively connected to said legs or standards

and extending longitudinally between said end supports and provided upon their ends with hooks, substantially as and for the purpose set forth. 15

In testimony that I claim the foregoing as my invention I have signed my name, in presence of the subscribing witnesses, this 10th day of May, 1899.

MARIE P. HENDERSON.
